DESIGN FOR A SWEATER OR SIMILAR ARTICLE

Hans Boepple, Valley Cottage, N. Y.

Application January 18, 1940, Serial No. 89,528

Term of patent 3½ years

To all whom it may concern:

Be it known that I, Hans Boepple, a citizen of the United States, residing in Valley Cottage, county of Rockland, State of New York, have invented a new, original, and ornamental Design for a Sweater or Similar Article, of which the following is a specification, reference being had to the accompanying drawing, forming a part thereof.

The figure is a front view of a sweater showing my design.

The characteristic feature of my design resides in the combination, on the sweater disclosed, of

the flat ribbon insertion forming zig-zag stripes on the open-work knitted ribbon body in association with the ribbed cuffs, yoke and waistband as shown.

The back of the sweater is identical with the front thereof except that the button opening and the border along the buttons are missing leaving the back as a whole piece.

I claim:

The ornamental design for a sweater or similar article, as shown and described.

HANS BOEPPLE.
